CHAIN ROLLER LINK

Vernon G. Kessler, 6747 Nebraska Ave.,
Omaha, Nebr. 68104

Filed May 15, 1972, Ser. No. 253,695

Term of patent 14 years

Int. Cl. D12—05

U.S. Cl. D8—261

FIG. 1

FIG. 2

FIG. 3

FIG. 4

FIG. 5

FIG. 1 is a perspective view of a chain roller link, the broken line showing of spaced links being for illustrative purposes only;

FIG. 2 is a top plan view of the chain roller link;

FIG. 3 is an end view thereof;

FIG. 4 is a side elevational view thereof; and

FIG. 5 is a bottom plan view thereof.

I claim:

The ornamental design for a chain roller link, substantially as shown and described.
